PORTABLE STOVE

Stanley F. Jackes, University City, and Frederick W. Pavey, Sunset Terrace, Mo., assignors to Jackes-Evans Manufacturing Company, St. Louis, Mo., a corporation of Missouri

Application January 15, 1934, Serial No. 706,750
Renewed June 10, 1935

7 Claims. (Cl. 126—65)

This invention relates to stoves, and with regard to certain more specific features, to portable stoves, particularly for burning coal and wood and for domestic or camp use.

Among the several objects of the invention may be noted the provision of a light, sheet-metal stove which may be manufactured by methods known to the sheet-metal stove industry; the provision of a stove of this class which may be readily knocked down and nested for shipment in compact packages; the provision of a stove of this class which shall have an improved form of combustion chamber and draft arrangement; and the provision of a stove of this class which shall have a pleasing and modern appearance. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which is illustrated one of various possible embodiments of the invention,

Fig. 1 is a perspective view of the stove;

Fig. 2 is a side elevation showing the rear end of the stove;

Fig. 3 is a horizontal section taken substantially on line 3—3 of Fig. 1;

Fig. 4 is a detail of a hinge element;

Fig. 5 is a vertical section taken on line 5—5 of Fig. 1 showing a door;

Fig. 6 is a rear elevation of the door;

Fig. 7 is a cross section taken on line 7—7 of Fig. 1;

Fig. 8 is a perspective view of the bottom piece of the stove;

Fig. 9 is a side elevation, parts being shown in section, showing one method of nesting the stove elements for shipment;

Fig. 10 is a view similar to Figure 1 showing another form of the invention;

Fig. 11 is a longitudinal section of the form of the invention shown in Fig. 10; and,

Fig. 12 is a fragmentary, sectional detail taken along line 12—12 of Fig. 10.

Similar reference characters indicate corresponding parts throughout the several views of the drawings.

Heretofore sheet iron stoves have been made in forms which not only have an ill appearance but which are difficult to ship because they cannot be knocked down and nested so as to form

a manageable package for any substantial number of stoves. They have furthermore had forms not well adapted to burning wood, such as circular, elliptical and like forms. This has been particularly true of wood burning stoves for indoor use.

Referring now more particularly to Fig. 1, there is shown at numeral 1 a body portion of the stove comprising a U-shaped sheet 3 forming the sides 5 and top 7. The sides 5 and top 7 are provided with indentations 9 for strengthening the otherwise plane surfaces. While these indentations are shown as ridges in the present embodiment, it is to be understood that they may be made according to other forms.

Rolled to the U-shaped piece 3 are end pieces 11 and 13 which, with the U-shaped piece 3, form a hollow frusto-pyramidal, having an open bottom. It is to be understood that instead of using a roll fastening, bolts and nuts, tongues and slots and/or retaining bands may be used for joining the parts 3, 11 and 13.

In Fig. 8 is shown the bottom 15 of the stove which comprises a flat-sheet having narrow frusto-pyramidal sides 17 at the base of which is outwardly rolled a bottom bead 19. This bottom telescopes through the lower opening of the stove so that the said rectangular opening seats behind the bead 19 (Fig. 1). If coal is to be used a grate is used on the bottom and a suitable ash door is placed in the bottom of the front member 5.

Holes 21 provide for fastening the bottom 15 to the frusto-pyramid. Corresponding holes are placed at the corners of the body 1, and also corresponding holes in supporting legs 23, so that single bolts hold the respective legs 23 and bottom 15. Corresponding holes in the legs 23 serve to permit application of bolts 25 for preventing rotation of said legs 23. The legs may be cast, forged or stamped.

It will be seen that the bottom edge of the body 1 is recessed behind the rolled bead 19 so that said bead 19 on the bottom 15 forms a trim for the bottom of the body 1. The positioning of the bead 19 outside of the lower edge of the frusto-pyramidal body 1 insures rigidity after the stove is assembled, because it tends to maintain the lower rectangular opening of the body 1 in proper form and prevents any incipient separation at the rolled seams between parts 5, 11 and 13.

The rearward wall 11 of the body portion 1 is provided with a smoke pipe 27 having a removable connection 29 so that the smoke pipe may be

taken off and/or rotated before reapplication, as indicated by the dotted lines.

The front wall 13 is formed with an indentation 31 having a bottom ledge 32 and providing a substantially vertical wall 33 having an indentation 34 for supporting a firing door 35.

The firing door 35, as shown at Fig. 5, is of special construction and consists of a bulged sheet 37 having a rolled edge 39 and an adjustable draft 10 control 41. Interiorly, a baffle 43 is spot welded about the edges of the bulge 37 but leaving an opening 45 at the bottom of the bulge, so that air entering the draft control 41 is forced downwardly, to be preheated as it flows over the baffle 15 43, and entering the stove at the opening 45 in a preheated condition. Rolled edges 47 on the opening which the door covers cooperate with rolled door edges 39 to improve the seal of the door 37 with respect to the surface 33.

20 The door 37 is mounted on hinge elements such as shown in Fig. 4. Each hinge element is fastened inside to the depressed portions 34 by means of a rivet hole 36 and comprises a hook portion 49 which is adapted to pass through a corresponding opening 51 within the rolled edge 39 of the door (see Fig. 6). By applying the hook 49 through the openings 51 and causing it to pass round the bead 39, the door may be hinged at as many places as may be desired. In the present example, two 25 hinges are used. A suitable latch 53 is used for holding the door shut.

In order to obtain primary air below the fire, the ledge 32 is provided with a plurality of openings 55 (see Figs. 1, 7 and 9) adapted to register 35 with a corresponding plurality of openings 57 in a sliding register piece 59. The register piece 59 is held to the face of the ledge 31 by a fastener 61 slidable in a slot 63. The degree of sliding movement of the register piece 59 and the recess 40 31 is such as to bring the openings 57 and 55 into or out of register. A finger piece 65 is turned up to function as a control.

The rear and front members 11 and 13 are beaded to the U-shaped central member 7 during 45 manufacture and these three pieces form a permanent frusto-pyramidal which may readily be nested with other like frusto-pyramids from other stoves of like or different size, thus making a compact nestible arrangement for shipment. At 50 the same time the frusto-pyramidal bottoms 15 may be stacked and laid with the stacked frusto-pyramids (see Fig. 9). The small number of miscellaneous parts such as the legs 23, pipes 27 and doors 35 may be removed and carried inside the frusto-pyramids.

Thus a plurality of stoves, when knocked down for shipping, take up little space. All of the body parts being made of sheet iron, the stove is light. 60 The gauge of the sheet iron is, however, substantial so as to provide a substantially rigid structure.

The frusto-pyramidal form of the stove has several advantages. This form provides a relatively 65 large rectangular bottom upon which logs or sticks of wood may lie in such a way that a maximum amount of wood may be placed in the stove at one time. No wood members need to lie at diagonals against the sides of the stove, as is necessary in the old elliptical and circular forms 70 of wood burning stove. The spreading nature of the downward regions of the interior assure ample space in which lies this wood, and the tapering features of the upper regions insure that there 75 will be no useless dead air pockets in the draft

circulating systems. At the same time, the radiating surfaces 5 are directed upwardly so as to provide the emission of heat in the direction most desired. Also, the flat top 7 may be used for supporting vessels to be heated without interference 5 from firing holes or smoke pipe attachments.

The rectangular firing door in the recess 31 provides not only ample room for placing wood but for inserting a shovel for the removal of ashes. The old type of wood stove having an 10 opening in the top was not easily cleaned, where- as this stove is.

In Figs. 10 to 12 is shown another form of the invention in which the frusto-pyramidal form is used but the central U-shaped portion 7 is so 15 articulated to the end members 11 and 13 so that these parts are separable for shipping purposes. This is accomplished by telescoping the end members 11 and 13 over the end portions of the U-shaped member 7 and providing bolt holes 20 through which bolts 2 may be passed. The bolts 2 also hold in position nickle-plated or like decorative beading 4.

Furthermore, in this embodiment of the invention the legs 23 are pressed integrally with the 25 end members 11 and 13 so that one shell is effective to form the stove and the legs thereof. In this case, the telescoping bottom 15 is provided with the same type of bead 19, except that the bead is relieved at points which are necessary for 30 positioning of the legs 23, as shown in Fig. 10. It will also be noted from Fig. 11 that the bottom 15 is illustrated at 6 as being corrugated for purposes of stiffening the same. This corruga- 35 tion may also be applied to the form of bottom shown in Fig. 8.

Another feature of the alternative form of the invention is that, instead of placing the smoke pipe connection on the rear end 11, it is placed in the top of the stove and in the U-shaped mem- 40 ber 7. This is accomplished by cutting an opening and forming a receiving bead 8 for the pipe nipple 10. This procedure reduces the top area 45 of the stove but still the flat area at this region is greater than that employed on previous wood stoves where the firing door was also on the top. It will be understood that although the smoke pipe connection in Figs. 10 to 12, is shown as being round, that it may also be elliptical if desired, and that in the latter case, it may also be placed 50 at or near the curved top portion of the back member 11.

Another feature in the alternative construction is that the door 35 is hinged at the bottom, as indicated by hinges 12. An adjustable draft inlet 55 14 is used below the door and an adjustable draft inlet 16 on the door. A draft deflector 43 has also been shown in connection with the door in the form of the invention shown in Figs. 10 to 12.

In view of the above, it will be seen that the 60 several objects of the invention are achieved and other advantageous results attained.

As many changes could be made in carrying out the above constructions without departing from the scope of the invention, it is intended that all 65 matter contained in the above description or shown in the accompanying drawings shall be interpreted as illustrative and not in a limiting sense.

We claim:

1. In a stove, a frusto-pyramidal sheet-iron body, said body having an opening at the bottom, a bottom adapted to fit said opening, said bottom having a raised frusto-pyramidal portion tele- 75 scoping with said body portion, and an exterior,

upwardly formed bead about the base of the bottom behind which the lower edge of the body portion is adapted to rest.

2. In a stove, a frusto-pyramidal body, said body consisting of an integral U-shaped central member having sloping sides, a separate sloping rearward member fastened to said central member and a separate sloping forward member fastened to said central member, said body having a bottom edge forming an opening, and a frusto-pyramidal bottom telescoping said body at said opening.

3. In a stove, a frusto-pyramidal body, said body consisting of an integral U-shaped central member having sloping sides, a sloping rearward member fastened to said central member and a sloping forward member fastened to said central member, said body having a bottom edge forming an opening, a frusto-pyramidal bottom telescoping said body at said opening, said bottom having a bead at its lower edge lying outside of the body edge when assembled.

4. In a stove, a frusto-pyramidal body, said body consisting of an integral U-shaped central member having sloping sides, a sloping rearward member fastened to said central member and a sloping forward member fastened to said central member, said body having a bottom edge forming an opening, a frusto-pyramidal bottom telescoping said body at said opening, said bottom having a bead at its lower edge lying outside of the body edge when assembled, said rearward member exclusively having a smoke pipe connection and said forward member exclusively having a firing door therein.

5. In a stove, a frusto-pyramidal body, said

body consisting of an integral U-shaped central member having sloping sides, a sloping rearward member fastened to said central member and a sloping forward member fastened to said central member, said body having a bottom edge forming an opening, a frusto-pyramidal bottom telescoping said body at said opening, said bottom having a bead at its lower edge lying outside of the body edge when assembled, said rearward member exclusively having a smoke pipe connection and said forward member exclusively having a firing door therein, said U-shaped central member having a substantially unbroken flat upper surface.

6. In a stove, a frusto-pyramidal body, said body having an opening at the bottom and downwardly extending legs from said body located at intervals, a bottom adapted to fit said opening, said body having a raised frusto-pyramidal portion telescoping with said body portion, said bottom having a beaded portion adapted to lie outside the edge of said opening except at points occupied by said legs.

7. In a stove, a frusto-pyramidal body, said body having an opening at the bottom and downwardly extending legs from said body located at intervals, a bottom adapted to fit said opening, said body having a raised frusto-pyramidal portion telescoping with said body portion, said bottom having a beaded portion adapted to lie outside the edge of said opening except at points occupied by said legs, said opening having a rectangular shape and said legs being located at the corners thereof.
